DESIGN FOR A VACUUM CLEANER BAG

Sigmund Gasner, New York, N. Y.; Julius Gasner
administrator of said Sigmund Gasner, deceased

Application August 27, 1945, Serial No. 121,665

Term of patent 14 years

(Cl. D9—2)

To all whom it may concern:

Be it known that I, Sigmund Gasner, a citizen of the United States, residing at New York city, in the county of New York and State of New York, have invented a new, original, and ornamental Design for a Vacuum Cleaner Bag, of which the following is a specification, reference being had to the accompanying drawing, forming part thereof.

In the drawing:

Fig. 1 is a side view of a vacuum cleaner bag, showing my new design;

Fig. 2 is a top plan view thereof;

Fig. 3 is a bottom plan view; and

Fig. 4 is a front view.

I claim:

The ornamental design for a vacuum cleaner bag, substantially as shown.

SIGMUND GASNER.
